UNITED STATES PATENT OFFICE

JOHN W. TATTER, OF CHICAGO, ILLINOIS, ASSIGNOR TO LEWIS DIFFERENTIAL COMPANY,
OF CHICAGO, ILLINOIS, A CORPORATION OF ILLINOIS

LEAK PREVENTING DEVICE

Application filed September 17, 1928. Serial No. 306,599.

My invention relates to devices in the nature of packing devices for preventing the leakage of fluid from valves and the cylinders of pumps, or the like, and to prevent the leakage of fluid past the pistons or valves in pumps, cylinders, or the like.

My invention is particularly adapted to be embodied in hydraulic brake systems of the kind described and claimed in my copending application, Serial No. 211,529, filed August 8, 1927, a particular object of the present invention being to provide improved devices for preventing the escape of fluid from the systems.

Another object of the invention is to provide devices of the kind described which will operate successfully over long periods of time and will not disintegrate or deteriorate when the mechanism in which they are embodied is subjected to much use.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a plan view of the chassis of an automobile upon which brake mechanism embodying the invention is mounted;

Fig. 2 is a section taken on line 2—2 of Fig. 1;

Fig. 3 is a view illustrating the manner in which some of the mechanism shown in Fig. 2 is assembled;

Fig. 4 is a section taken on line 4—4 of Fig. 1;

Fig. 5 is a section taken on line 5—5 of Fig. 4;

Fig. 6 is a view illustrating the manner in which some of the mechanism shown in Fig. 4 is assembled;

Fig. 8 is an enlarged section taken on line 8—8 of Fig. 7;

Fig. 9 is a view illustrating the manner in which some of the mechanism shown in Fig. 8 is assembled;

Fig. 10 illustrated a modified form of the invention embodied in mechanism which may be used in place of the mechanism illustrated in Fig. 8;

Fig. 11 is a central longitudinal section through the improved sealing device shown in Fig. 10, the improved device being contracted in Fig. 11;

Fig. 12 is a fragmentary section through brake mechanism adapted to be employed in place of the brake mechanism shown in Fig. 7;

Fig. 13 is an enlarged section taken on line 13—13 of Fig. 12;

Fig. 14 is a central section taken through the improved sealing device shown in Fig. 13 to illustrate how the improved sealing device is expanded when it is assembled with the remainder of the brake mechanism;

Fig. 15 is a section taken through brake mechanism adapted to be employed in place of the brake mechanism shown in Figs. 7, 8, 12 and 13, a sealing device substantially identical to that shown in Figs. 13 and 14 being employed in connection with the mechanism shown in Fig. 15;

Fig. 16 is a section taken through brake mechanism which may be employed in place of the mechanism shown in Figs. 7, 8, 12, 13 and 15;

Fig. 17 is a section taken through brake mechanism which may be employed in place of the mechanism shown in Fig. 4;

Fig. 18 is an end view of a packing member or seal forming part of the mechanism shown in Fig. 17; and

Fig. 19 is a section taken through brake mechanism which may be employed in place of the mechanism shown in Figs. 4 and 17.

While I have disclosed my present invention in connection with brake mechanism, it is to be understood that the invention is limited to this use only to the extent indicated in the appended claims.

Referring for the present to Figs. 1 to 9,

inclusive, wherein I have shown several forms of the invention embodied in brake mechanism which is mounted upon a chassis 10, the brake mechanism is shown assembled in Fig. 1 to facilitate the task of disclosing this invention. It will be noted that this mechanism resembles that shown in my copending application, Serial No. 211,529, filed August 8, 1927, and operates in substantially the same manner so that a detailed description thereof need not be given in this instance. Briefly, it comprises brakes 16 and 17 provided for the front and rear wheels 18 and 19, respectively, of the chassis 10. The brakes are of the hydraulic or fluid operated type and are operatively connected through pipes or tubing 20 with a pipe line 21 preferably arranged transversely of the chassis 10. A substantially vertically disposed pipe or tube 23 operatively connects the pipe or tube 21 with a filling and regulating device which is designated generally by the reference character 25.

Referring to Figs. 1 and 4, it will be noted that a foot or brake pedal 27 is adapted to displace a piston 28 arranged in a chamber 29 which is formed in a cylinder 30, the chamber 29 being arranged to communicate with the pipe 21 through ports 32 which are formed in a cap 33 closing one end of the chamber 29.

Some details of the construction of the filling and regulating device 25 differ from the corresponding details of construction of the filling and regulating device shown in my copending application, Serial No. 211,529 so that they may more readily cooperate with and form parts of improved means for effectively sealing the filling and regulating device (see Fig. 2). It will be noted that the filling and regulating device 25 comprises a receptacle 35 which communicates through a port 36 with a chamber 37 that is formed in a cylinder 38 and a cap 39, the cap 39 being arranged to close one end of the cylinder 38. The chamber 37 also communicates with the pipe 23 through a port 40 and the flow of fluid or liquid through the ports 36 and 40 is controlled by valves 42 and 43, respectively. The stem of the valve 43 is provided with an outwardly extending annular flange 44 which is slidably journaled in a cylindrical chamber 45, a spring 46 being positioned in the chamber 45 to yieldingly hold the valve 43 in a position wherein it does not close the port 40. The chamber 45 is formed in a housing 50 in which the receptacle 35 and the chamber 37 are also formed. One end of the chamber 45 is closed by a cap 48 which is secured in place by bolts 49, or the equivalent, and clamped between the cap 48 and the housing 50 is a member 51 which is preferably formed from rubber, or the like, but may be formed from any suitable elastic material. The member 51 is preferably pro-

vided with an integral annular flange 52 positioned in an annular groove 53 formed in the housing 50. The member 51 has a substantially central aperture 54 which is bounded by an annular flange 56, the annular flange 56 being adapted to fit snugly around a boss 57 preferably formed integral with the valve 43. It will be noted that the diameter of the chamber 45 is slightly larger than that of a chamber 58 formed in the cap 48 so that the cap forms a stop which limits the distance the valve 43 may be displaced to the left (Fig. 2) by the spring 46. The central portion of the member 51 is preferably clamped between the annular flange 44 and a piston member 60 which is slidably journaled in the chamber 58, the piston member 60 being rigidly secured to the valve 43 by a screw 61, or the equivalent. The construction is preferably such that the member 51 is compressed when it is clamped between the cap 48 and the housing 50 and between the flange 44 and the piston member 60. Disposed within the piston member 60 and interposed between the head of the screw 61 and a head 63 formed upon a screw-threaded post 65 is a steel ball 66, the post 65 being screw-threaded in the cap 48 and being preferably provided with a handle member 67 whereby it may be rotated to displace the ball 66 and also the piston member 60 and the valve 43 against the action of the spring 46.

As set forth in my above-mentioned copending application, the valve 43 is alternately closed and opened during the process of producing a partial vacuum in the system before the oil or other fluid is introduced into the system. After the system has been properly filled with any suitable fluid, the pressure maintained in the system will tend to cause the fluid to escape from the system through the outer end of the chamber 45. However, such leakage is prevented by the member 51 which hermetically seals the outer end of the chamber. The member 51 does not interfere with the operation of the valve 43 as it is flexible and elastic.

Disposed within the chamber 37 is a fabricated piston 70 which preferably comprises complementary members 71 and 72 between which a portion of a member 73 is clamped, the member 73 being preferably formed from rubber, or the equivalent, (see Fig. 2). As shown, the member 73 is preferably substantially cup-shaped and preferably comprises a relatively thin substantially cylindrical wall 74 which is preferably formed integral with an apertured disc 75, the apertured disc 75 being relatively thick and being the portion which is clamped between the members 71 and 72. In practice, I have found it advantageous to make the disc 75 at least twice as thick as the cylindrical wall 74 and I have also found it advantageous to compress the disc between the members 71 and 72. The

inner surface of the disc 75 is preferably provided with an annular groove 77 arranged concentric with an aperture 78 formed in the disc and the member 71 is preferably provided with an annular flange 79 adapted to engage the annular groove 77. This construction tends to prevent distortion of the material disposed around the aperture 78 and this aperture is preferably of a diameter which insures that it will fit snugly around a boss 80 preferably formed integral with the member 71. An annular flange 82 is preferably formed integral with the cylindrical wall 74 and is preferably clamped between the housing 50 and the cap 39, screws 83, or the equivalent, being preferably provided to rigidly secure the cap to the housing. At the outer margin of the annular flange 82, I preferably provide a second annular flange 84 adapted to rest in an annular groove 85 formed in the housing 50.

The piston member 72 is preferably rigidly secured to the piston member 71 by means comprising a collar 86 which is screw-threaded into the piston member 71 and is provided with an annular flange or head 87 adapted to clamp the piston member 72 against the piston member 71, a gasket 89 of any suitable material being preferably positioned between the flange 87 and the piston member 72. Screw-threaded through the collar 86 is a post 90 which is rotatably journaled in the cap 39 and is held against longitudinal displacement relative to the chamber 37 by a collar 91 and an annular flange 92, the annular flange 92 being preferably formed integral with the post 90. The outer end of the post 90 is preferably provided with a handle member 94 whereby the post may be rotated to displace the cylinder 70 in the chamber 37.

In Fig. 3 I have shown an "exploded" view of the piston members 71 and 72 and the member 73 to illustrate the appearance and the preferred dimensions of the member 73 when it is not distorted by the members 71 and 72. In practice, I find it preferable to mold the member 73 so that the internal diameter of its cylindrical wall 74 is less than the diameter of the cylindrical surface of the member 71 and so that the external diameter of the disk portion 75 is considerably less than the normal external diameter of the cylindrical wall 74. Then when the member 73 is assembled with the members 71 and 72 and the disk portion 75 is compressed, it will expand laterally until its external diameter is substantially equal to the internal diameter of the chamber 37. The disk portion 75 is preferably compressed about 40% of its normal thickness so that it is firmly clamped between the members 71 and 72 and is not readily displaced therefrom. Obviously, the member 73 forms a seal for the chamber 37 and prevents leakage from it.

Referring now to Figs. 4, 5 and 6, it will be noted that the chamber 29, in which the piston 28 is slidably journaled, is sealed by a cup-shaped member 95 comprising a substantially cylindrical wall 96 with which the disk portion 97 is preferably formed integral. The member 95 is preferably formed of rubber or the equivalent. The disk portion 97 is provided with an aperture 98 arranged to fit snugly around a boss 99 which is preferably formed integral with a member 100 and the member 100 is in reality an extension of the piston 28. As shown, the boss 99 seats in a recess 102 formed in the piston 28 and the member 100 is secured to the piston by a bolt 103. Interposed between the member 100 and one end of the chamber 29 is a compression spring 105 which tends to displace the piston 28 to the right (Fig. 4). Obviously, when the piston 28 is displaced to the left (Fig. 4) by means of the brake lever 27, fluid disposed in the left hand end of the chamber 29 will be discharged therefrom through the ports 32 into the pipe line 21. However, when pressure is removed from the brake pedal 27, the spring 105 will displace the piston 28 to the right (Fig. 4) and restore the foot pedal 27 to its original position.

It will be noted that the external diameter of one end of the member 100 is substantially equal to the internal diameter of that portion of the chamber 29 formed in the cap 33, this portion of the chamber 29 being smaller in diameter than that portion in which the piston 28 is slidably journaled. This construction provides an annular space 108 between the member 100 and the cylindrical surfaces of the larger portion of the chamber 29 and accommodates the cylindrical wall 96 of the member 95. In the preferred embodiment of the invention, the cylindrical wall 96 fits loosely in the annular space 108 throughout the greater portion of its length but it will be noted that the right hand end (Fig. 4) of the member 100 is provided with a head 109 which is of larger diameter than the normal internal diameter of the cylindrical wall 96 (see Fig. 6). An annular groove 112 formed in the head 109 accommodates an annular flange 113 preferably formed integral with the disk portion 97 and the disk portion 97 is preferably compressed between the piston 28 and the member 100 to such an extent that it forms a seal to prevent leakage from the chamber 29. The flange 113 holds the disk portion 97 firmly in place between the piston 28 and the member 100. As best illustrated in Fig. 6, the normal external diameter of the cylindrical wall 96 is preferably less than the diameter of the piston 28 when the member 95 is not assembled with the piston and its extension member 100. However, when the disk portion 97 is clamped between the member 100 and the piston 28, it expands laterally

until it is of a diameter substantially equal to the diameter of the large portion of the chamber 29. It will be noted that the boss 99 seats against the bottom surface of the recess 102 and prevents the member 100 from cutting through the disk portion 97. The member 95 is preferably provided with an integral flange 95a adapted to be compressed between the cylinder 30 and the cap 33 and formed integral with the flange 95a is a flange 95b which engages an annular shoulder 33a formed on the cap 33. The flange 95b prevents the flange 95a from being pulled out from between the cap and cylinder.

Referring now to Figs. 7 to 9, inclusive, wherein I have illustrated the details of one of the rear brakes 17, the reference character 120 designates the brake drum and the reference character 121 designates the brake band. The brake band is provided with a lining 122 engageable with the internal cylindrical surface of the brake drum 120. Means for expanding the brake band 121 comprises a piston 123 which is slidably journaled in a chamber 124 formed in a cylinder 125, the cylinder 125 being closed at one end by a cap 126 which is provided with a port 127. The port 127 also communicates with one of the pipes or tubes 20 so that fluid will be forced into the chamber 124 when the brake pedal 27 is depressed. The piston 123 comprises members 127 and 128 which are secured to each other by a bolt 129. As shown, the member 128 is provided with a substantially cylindrical boss 130 which projects into a recess 131 formed in the member 127, the boss 130 being arranged to abut against the bottom surface of the recess 131. Clamped between the members 127 and 128 is a cup-shaped member 132 which is preferably formed of rubber, or the equivalent, and preferably comprises a thin cylindrical wall 133 formed integral with the disk portion 134 which forms the bottom of the cup-shaped member 132. An inwardly projecting annular flange 136 formed integral with the disk portion 134 projects into an annular groove 137 formed in the member 128. The construction is preferably such that when the boss 130 abuts the bottom surface of the recess 131, the disk portion 134 is compressed and is firmly held in place between the members 127 and 128. As shown in the "exploded" view (Fig. 9) the external diameter of the cylindrical wall 133 is less than the diameter of the chamber 124 when the member 132 has not been assembled with the members 127 and 128. However, when the disk portion 134 is compressed between the members 127 and 128 it expands laterally until it becomes of a diameter substantially equal to the diameter of the chamber 124. At the end opposite the disk portion 134, the cylindrical wall 133 is provided with an outwardly projecting annular flange 139 which is, in turn, provided with an annular flange 140 adapted to seat in

a groove 141 provided in the cap 126. The annular flange 139 is compressed between the cap 126 and the cylinder 125 in such manner that it effectively seals the joint between the cap and the cylinder. The annular flange 140 prevents the flange 139 from being pulled out of the space between the cap and the cylinder.

Projecting inwardly from the ends of the brake band 121 are bracket members 142 and 143 which engage slots 144 and 145, respectively, provided in the cap 126 and the member 127, respectively. Obviously, when fluid under pressure is introduced into the left hand end (Fig. 8) of the chamber 124 through the port 127, the piston 123 will be displaced to the right (Fig. 8) and will expand the band 121. Also as explained in my copending application, Serial No. 211,529, filed August 8, 1927 the cap and cylinder can move to the left (Fig. 8) and displace the bracket 142 together with that end of the band to which it is secured.

To prevent dust, dirt, or the like, from entering the cylinder 124 through the right hand (Fig. 8) end thereof, I preferably provide a flexible sleeve 150 which has one end clamped to the cylinder 125 and has its other end clamped to an annular flange 152 provided upon the outer end of the member 127. The flexible sleeve 150 is preferably provided with an inwardly extending annular flange 153 engageable with an annular groove 155 formed in the flange 152. Intermediate its ends, the flexible sleeve 150 is provided with a plurality of annular folds 157 so that the sleeve may elongate or contract with the movement of the piston 123. The sleeve 150 may be made of leather but is preferably made of rubber, or the equivalent.

In Figs. 10 and 11 I have shown a modified form of the apparatus shown in Figs. 8 and 9. Thus, I provide a cylinder 160 in which a piston 161 is slidably journaled, the piston being formed from a substantially cylindrical member 162 which is rigidly secured to a member 163 by means comprising a tube 164 preferably formed integral with a bracket member 165. A port 166 formed in the bracket member 165 and the tube 164 provides means whereby fluid may be forced into the cylinder 160 from one of the pipes or tubes 20 shown in Fig. 1, it being readily understood that the mechanism shown in Figs. 10 and 11 can be used in place of the mechanism shown in Figs. 8 and 9. Slots 170 and 171 provided in the bracket member 165 and the cylinder 160, respectively, are adapted to cooperate with bracket members similar to the bracket members 142 and 143 shown in Fig. 7.

The member 163 is screw-threaded upon the tube 164 and it is provided with a chamber 172 into which fluid may be introduced by way of the port 166 and it will be noted that the chamber 172 communicates with the

exterior surface of the member 163 through a port 174 so that fluid introduced into the chamber 172 by way of the port 166 will exert pressure against a member 175 which is preferably carried by the member 163 and is preferably formed from rubber, or the equivalent. In this embodiment of the invention, the member 175 comprises a relatively thin wall 177 enclosing a chamber 178 into which the member 163 may be forced through an aperture 179 formed in a disk portion 180, the disk portion 180 being preferably formed integral with the thin wall 177. The disk portion 180 is preferably provided with an inwardly extending annular flange 181 adapted to engage a groove 183 formed in the member 163. The end portion 180 is relatively thick and when the member 175 is assembled with the members 162 and 163, it is compressed so that it forms a seal between these members. The amount the disk portion 180 can be compressed is limited by a boss 185 which is formed upon the member 162 and projects into a recess 186 formed in the member 163. The internal diameter of the member 175 is normally less than the external diameter of the member 163 so that it is expanded when the member 163 is forced into it. This is shown by dotted lines in Fig. 11. When the apparatus shown in Fig. 10 is operated, fluid is forced into the chamber 172 by way of the port 166 and it passes through the port 174 to displace the cylinder 160 to the right (Fig. 10) and to displace the piston 161 to the left (Fig. 10), the member 175 being elongated. As the disk portion 180 seals the joint between the members 162 and 163, fluid urged through the port 174 will be retained within the member 175 and will not escape or leak from the cylinder 160.

In Figs. 12, 13 and 14, I have shown another form of the invention embodied in apparatus which can also be used in place of the apparatus shown in Figs. 7, 8 and 9. Thus, I have shown a bracket comprising a brake drum 195 which cooperates with a brake band 196 having a brake lining 197. Interposed between the ends of the brake band 196 is means for expanding the brake comprising a bracket member 198 and a cylinder 199, the cylinder 199 being rigidly secured to the bracket member. A port 200 formed in the bracket member 198 is adapted to communicate with a pipe 202 which is the equivalent of one of the pipes 20 shown in Fig. 1 so that fluid may be forced into the cylinder. Slidably journaled in the cylinder 199 is a piston 203 to which a rod 204 is rigidly secured, the outer end of the rod being adapted to engage a slot 205 formed in a bracket member 206 which is rigidly secured to one end of the brake band 196. Secured to the other end of the brake band 196 is a bracket member 207 provided with a slot 208 which is engaged by a lug 209 preferably formed integral with the bracket member

198. Interposed between the piston 203 and a substantially cylindrical lug 210 formed integral with the bracket member 198 is a cup-shaped member 211 which is preferably formed from rubber, or the equivalent. The cup-shaped member 211 is preferably provided with a substantially cylindrical wall 213 and formed integral with the wall 213 is an imperforate disk portion 214 against which fluid may be forced through the port 200. It will be noted that the disk portion 214 is relatively thick as compared with the cylindrical wall 213 and that the cylindrical wall 213 is provided with an integral outwardly projecting annular flange 215 which, at its outer end, is provided with an annular flange 216, the annular flange 216 being arranged in a groove 217 formed in the bracket member 198. The annular flange 215 is clamped securely between the bracket member 198 and the cylinder 199, the flange 215 being compressed so that it forms a seal in the joint between the bracket member 198 and the cylinder 199.

The wall 213 is preferably tapered as shown in Fig. 14 when the cup-shaped member 211 is not assembled with the boss 210 but the construction of the cup-shaped member 211 is such that when it is forced upon the boss 210, the disk portion 214 is expanded laterally so that its diameter is substantially equal to the diameter of the chamber within the cylinder 199. When fluid under sufficient pressure is introduced into the port 200, it displaces the disk portion 214 to the right (Fig. 13) and elongates the wall 213. This displacement of the disk portion 214 causes like displacement of the piston 203 and it, in turn, displaces the bracket member 206 to expand the brake band 196. The bracket member 198 is arranged between the ends of the brake band 196 and is relatively free to move toward the left (Fig. 13) so that when fluid under sufficient pressure is introduced into the port 200, both ends of the brake band are displaced in directions away from each other. It will be noted that the cup-shaped member 211 effectively seals the inner end of the port 200 so that fluid can not escape or leak from the cylinder 199.

To prevent dust, dirt, or the like, from entering the cylinder 199 through the right hand (Fig. 13) end thereof, I preferably provide a flexible sleeve 220 of rubber, or the equivalent, which has one of its ends clamped to the rod 204 and has the other of its ends clamped between one end of the cylinder 199 and a collar 222 which is screw-threaded upon the cylinder.

In Fig. 15 I have shown a modified form of the apparatus shown in Fig. 13, in which modified apparatus, a cup-shaped member 230 formed of rubber, or the equivalent, and substantially identical with the afore-mentioned cup-shaped member 211 is employed. The

130

apparatus shown in Fig. 15 comprises a bracket member 231 and a cylinder 232 which have the same functions as the bracket member 198 and the cylinder 199, respectively, shown in Fig. 13. The bracket member 231 is provided with a port 233 through which fluid under pressure may be urged against a disk portion 234 forming part of the cup-shaped member 230. Slidably journaled in the cylinder 232 is a piston 235 provided with a slot 236 engageable by a bracket member 237 which may be rigidly secured to one end of a brake band and corresponds to the bracket member 206 shown in Fig. 12. A slot 239 formed in the bracket member 231 is engaged by a bracket member 240 which corresponds to the bracket member 207 of Fig. 12. Obviously, when fluid under sufficient pressure is introduced into the port 233, the disk portion 234 will be displaced to the right (Fig. 15) so that there will be relative movement between the bracket member 231 and the piston 235 to expand the brake band to which the bracket members 240 and 237 are attached.

Referring now to Fig. 16 wherein I have shown apparatus adapted to be employed in place of the apparatus shown in Fig. 8, the reference character 242 identifies a bracket member and the reference character 243 identifies a cylinder which is rigidly secured to the bracket member. The bracket member 242 and the cylinder 243 perform substantially the same functions as the aforementioned bracket 198 and cylinder 199, respectively, and the cylinder 243 slidably journals a piston 244 which abuts against a conical wall 245 forming part of a cup-shaped member 246 which is preferably formed from some elastic material such as rubber, or the equivalent. The cup-shaped member 246 also comprises a substantially cylindrical wall 247 which is provided with an outwardly extending integral flange 248 and at its outer margin, the flange 248 is provided with an annular flange 249 adapted to engage an annular groove 250 formed in the bracket member 242. Projecting into the cup-shaped member 246 and fitting snugly therein is a boss 252 which is preferably formed integral with the bracket member 242. A port 253 formed in the bracket member 242 and the boss 252 communicates with a pipe 255 which may be connected to the pipe 21 shown in Fig. 1. Engaging slots 256 and 257 provided in the bracket member 242 and the piston 244, respectively, are bracket members 258 and 259, respectively, which have the same functions as the aforementioned bracket members 142 and 143 shown in Fig. 8.

It will be noted that the boss 252 is provided with a conical end wall 260 which abuts against the inner side of the conical wall 245 and it will also be noted that the disk 244 has a conical depression 262 into which the conical wall 245 projects. The flange

248 is clamped between the bracket member 242 and the cylinder 243 and is compressed sufficiently to form a liquid tight seal at this point. The annular flange 250 prevents the flange 248 from being drawn from between the bracket member 242 and the cylinder 243 when the cylindrical wall 247 is tensioned.

When fluid under sufficient pressure is introduced into the port 253 it exerts pressure against the inner side of the conical wall 245 and displaces this wall, the cylindrical wall 247 being elongated. Such displacement of the conical wall 245 causes relative displacement between the bracket member 242 and the piston 244 so that the ends of the brake band (not shown) to which the bracket members 258 and 259 are attached move away from each other to cause the brake band (not shown) to expand. Obviously, the cup-shaped member 246 constitutes means to prevent leakage of fluid from the cylinder 243.

In Figs. 17 and 18 I have shown apparatus adapted to be used in place of the apparatus shown in Fig. 4. A two-part piston 270 is shown comprising members 271 and 272 which are rigidly secured to each other by a bolt 273. A cylindrical boss 274 preferably formed integral with the member 271 seats in a recess 275 formed in the member 272, the outer end of the boss being adapted to abut against the bottom of the recess 275. The bolt 273 passes through an aperture 278 formed in the boss 274 and is screw-threaded into the member 272. The member 272 is slidably journaled in a chamber or bore 279 formed in a housing member 280 and the member 271 is slidably journaled in a chamber or bore 291 formed in a cap 292 which closes one end of the chamber or bore 279. It will be noted that the members 271 and 272 are round in cross section and are coaxially disposed. Interposed between the member 271 and one end of the chamber or bore 291 is a compression spring 294 which urges the piston 270 to the right (Fig. 16). Means comprising a brake pedal 296 is provided for displacing the piston 270 to the left (Fig. 16) against the action of the spring 294. A port 299 formed in the cap member 292 communicates with a transversely extending bore 300. The transverse bore 300 provides means whereby the bore 299 may communicate with pipes (not shown) which are the equivalent of the pipes 21 shown in Fig. 1. Clamped between the members 271 and 272 is a bottom or end wall 303 of a cup-shaped member 304 which also comprises a substantially cylindrical wall 305, the cylindrical wall 305 terminating at one end in an annular flange 306 which, at its outer end is provided with an annular flange 307 engageable with a groove 308 formed in the cap member 292. The cup-shaped member 304 is preferably made from rubber, or the equivalent, and it will be noted that its cylindrical wall 304 is relatively thin as compared with the thick-

ness of the end or bottom wall 303. The end or bottom wall 303 is provided with a central aperture 310 which fits snugly around the boss 274 and bounding the aperture 310 is an 5 annular flange 311 which is preferably formed integral with the wall 303 and preferably projects into an annular groove 312 formed in the member 271. On the outer side of the bottom or end wall 303 is a frusto-conical member 315 preferably formed integral with the wall 303 and snugly fitted in a frusto-conical recess 317 formed in the member 272. In other words, the recess 317 is undercut and the member 315 is fitted into 10 it in such manner that it is not removable therefrom and can only be removed therefrom when the member 271 has been withdrawn from the cup-shaped member 304. The member 315 is inserted in the recess 317 by temporarily deforming or depressing it 15 and working it into the recess before the member 271 is assembled with the member 272. The marginal portion of the end wall 303 is compressed between the members 271 and 272 to form a liquid tight seal between 20 and the annular flange 306 is compressed between the housing 280 and the cap member 292 to form a liquid tight seal at this point. Obviously, when the brake lever or pedal 25 296 is displaced in a counter clockwise direction (Fig. 16) against the action of the spring 294 fluid disposed in the chamber or bore 291 will be discharged from the bore or chamber 291 through the bores 299 and 300 to 30 the brakes with which these bores communicate. Then when the brake pedal is permitted to return to its original position, the fluid is forced back into the bore or chamber 291 and displaces the piston 270 to the 35 right (Fig. 16) and elongates the cylindrical wall 304. When the cup-shaped member 304 is not assembled with the members 271 and 272 its 40 external diameter is less than the diameter of the bore or chamber 279 so that both the cylindrical wall 304 and the end wall 303 are expanded to the diameter of the bore or chamber 279 when the member 304 is assembled with the members 271 and 272, the end 45 wall 303 being compressed longitudinally of the member 304 but being expanded laterally thereof. Of course, the marginal portion of the member 303 is compressed more than the central portion thereof. Referring now to Fig. 19 wherein I have 50 shown still another form of apparatus which may be employed in place of the apparatus shown in Fig. 4, the reference character 320 designates a housing having a bore or chamber 321 which is closed at one end by a cap member 322 having a bore or chamber 323, the bore or chamber being coaxially disposed with respect to the bore or chamber 321. Disposed in the bores or chambers 321 and 323 55 is a two-part piston 325 which comprises members 326 and 327, the members 326 and 327 being secured to each other by a bolt 328 which projects through an aperture 329 formed in a cylindrical boss 330 preferably formed integral with the member 326. The bolt is screw-threaded into a member 327 and it will be noted that a recess 330 is provided in the member 327 which recess accommodates the boss 320, the boss being adapted to abut against the bottom surface of the recess. Interposed between one end of the bore or chamber 323 and the member 326 is a compression spring 332 which yieldingly urges the piston 325 to the right (Fig. 18). Means comprising a foot pedal 334 is provided for displacing the piston 325 to the left (Fig. 18) against the action of the spring 332. A transverse bore 337 provided in the cap member 322 provides means whereby a bore 336 may communicate with pipes (not shown) which are the equivalent of the pipes 21 shown in Fig. 1, the bore 336 being in communication with the chamber 323. Clamped between the members 326 and 327 is a bottom or end wall 339 of a cup-shaped member 340 which also comprises a substantially cylindrical wall 341 formed integral with the end or bottom wall 339. The member 340 is preferably formed from rubber, or the equivalent. The cylindrical wall 341 is provided with an outwardly extending annular flange 322 which is compressed and clamped between the cap member 322 and the housing member 320. An annular flange 343 formed at the outer edge of the annular flange 342 engages an annular groove 344 formed in the cap member 322. It will be noted that the bottom or end wall 339 is relatively thin where it joins the cylindrical wall 341 and that it increases in width toward its center until it is cut away at 350 and 351 to engage the boss 340 and a boss 352, respectively, the boss 352 being formed upon the member 327. An annular flange 355 forming part of the end wall 339 is relatively thin in comparison with the remainder of the end wall and is clamped between the boss 352 and a shoulder 357 formed upon the boss 330. It will be noted, however, that the greater portion of the end wall is thicker than the cylindrical wall 341 and that the tapered portion of the end wall 339 fits snugly and is compressed in an undercut annular groove 360 formed partly in the member 326 and partly in the member 327. Obviously, the wall 339 cannot be withdrawn from its position in the groove 360 unless the member 326 is withdrawn from the member 340. Therefore, when the wall 341 is tensioned there is no lateral displacement of the end wall 339. When the brake pedal 334 is displaced in a counter clockwise direction (Fig. 18) against the action of the spring 332, fluid disposed in the bore or chamber 323 will be discharged through the bores 336 and 337 to the pipes 130

which are not shown which are the equivalent of the pipes 21 in Figs. 1 and 4. Then when the brake pedal 334 is permitted to return to its original position, the fluid will return to the bore or chamber 323 and with the assistance of the spring 322 will displace the piston 325 to the right (Fig. 18). This will tension or elongate the cylindrical wall 341.

Before the cup-shaped member 340 is assembled with the members 326 and 327 its external diameter is considerably less than the diameter of the bore or chamber 321. However, when the end wall 339 is compressed between the members 326 and 327, the end wall expands laterally until it assumes the diameter of the bore or chamber 321 and the cylindrical wall 341 is expanded, of course, over the member 326.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a connection between a cylindrical chamber and a member operable therein, packing means therefor comprising a cup-shaped rubber packing member adapted to be clamped to the wall of the chamber and having a cylindrical side wall of relatively thin wall section whereby said cylindrical side wall may be readily stretched axially thereof, said cup shaped member having a bottom wall integral with said side wall, said bottom wall extending transversely of the axis of said cylindrical side wall, said bottom wall having a relatively thick wall section whereby to resist deflection outwardly thereof when subjected to relatively high fluid pressure within said cup-shaped packing member.

2. In a connection between a cylindrical chamber and a member operable therein, packing means therefor comprising a cup-shaped rubber packing member adapted to be clamped to the wall of the chamber and having a cylindrical side wall of relatively thin wall section whereby said cylindrical side wall may be readily stretched axially thereof, said cup-shaped member having a bottom wall integral with said side wall, said bottom wall extending transversely of the axis of said cylindrical side wall, said bottom wall having a relatively thick wall section whereby to resist deflection outwardly thereof when subjected to relatively high fluid pressure within said cup-shaped packing member, said bottom wall section being at least twice as thick as said side wall section.

3. In a connection between a cylindrical chamber and a member operable therein,

packing means therefor comprising a cup-shaped rubber packing member adapted to be clamped to the wall of the chamber and having a cylindrical side wall of relatively thin wall section whereby said cylindrical side wall may be readily stretched axially thereof, said cup-shaped member having a bottom wall integral with said side wall, said bottom wall extending transversely of the axis of said cylindrical side wall, said bottom wall having a relatively thick wall section whereby to resist deflection outwardly thereof when subjected to relatively high fluid pressure within said cup-shaped packing member, said bottom wall section being at least twice as thick as said side wall section, said bottom wall extending substantially in a plane transversely to the axis of said cylindrical side wall.

In testimony whereof, I have hereunto signed my name.

JOHN W. TATTER.
